UNITED STATES PATENT OFFICE.

ROBERT E. TORNBLOM, OF BROOKLYN, NEW YORK.

CINERARY RECEPTACLE.

Application filed February 26, 1923. Serial No. 621,351.

To all whom it may concern:

Be it known that I, ROBERT E. TORNBLOM, a resident of the borough of Brooklyn, in the county of Kings, city and State of New York, have invented certain new and useful Improvements in Cinerary Receptacles, of which the following is a specification.

This invention relates to detrital receivers of the portable type, particularly adapted 10 for the collection of cigar ashes and analogous waste matter, and it has especial reference to closures for the same.

The main object of the invention is to produce an improved container of the type 15 aforesaid, designed for the personal and individual use of persons addicted to smoking tobacco, in any form thereof, and to make it of such shape, size, and weight as to render it convenient to carry in the 20 pocket, so that a smoker may have always at hand a clean and sanitary receptacle wherein to deposit the residue of a pipe, cigar or cigarette, wherever facilities of that sort are wanting.

25 Another object is to provide a receptacle of the character described with a dual closure, consisting of a pair of superimposed movable members, so constructed that when both are shut the inner member serves to 30 prevent the contents of the receptacle from coming into contact with the under face of the outer member.

A further object is the provision in a 35 receptacle of the nature set forth, of means operating interrelatively to lock together the superimposed members pertaining to its cover, whenever they are in closed position.

Still another object in producing a receptacle of the kind specified is to insure the 40 proper and timely shutting of the same, through the medium of an interconnecting element carried by one of the pair of superimposed members and adapted to engage the other member thereof in such a way as to 45 make it imperative to close the latter fully before the interlocking of the two members can be effected.

A still further object is the production 50 of a receptacle of the class mentioned having a dual closure as above stated, wherein the upper member includes an element adapted, when outwardly exposed, to receive an object lodged thereon, and acting as well, upon inversion, to lock the sublying member 55 in the relative position thereto assigned.

An additional object is to supply a receptacle of the genus alluded to with a cover comprising a fixed outer portion, besides the dual closure composed of the movable members aforementioned, the whole being 60 so constituted that the pair of movable members will co-operate one with the other only in their closed positions, while the inner member alone of the pair will at all times be coacting with the fixed outer portion. 65

A subsidiary object is to furnish a receptacle of the sort referred to with appropriately disposed guides, one of which shall be engaged by the fixed outer portion of the cover and afford a connection for the 70 correspondingly located movable member thereof, the other guide meanwhile receiving the movable inner member and maintaining it in functional relation to both the exteriorly situated parts of the cover before men- 75 tioned.

A general object is to obtain a practical receptacle for the purpose contemplated, which shall be easily operated; pleasing in appearance; quickly assembled, and not 80 liable to get out of order; besides admitting of economical manufacture.

Other objects and advantages of the invention will become apparent as the specification proceeds. 85

With the aforesaid objects in view, the invention consists of the novel combinations and arrangements of parts hereinafter described in their preferred embodiments, pointed out in the subjoined claims, and illustrated on the annexed drawing, wherein like parts are designated by the same reference characters throughout the several views.

In the said drawing:—

Figure 1 is a top plan view of this improved device, looking down upon its movable parts in their closed positions; 95

Fig. 2 is a side elevation of the same, looking up from the lower edge of the preceding figure, the movable parts thereof being 100 shown open;

Fig. 3 is a central longitudinal section taken along the line 3—3 of Fig. 1, looking upwardly, the parts appearing in corresponding relation; 105

Fig. 4 is an end elevation, looking from the left-hand side of Fig. 2, the parts corresponding in position to those represented in Fig. 1; and

Fig. 5 is a similar elevation, looking from 110

the same side of Fig. 2, but with the visible movable parts open.

Generally described, the invention under consideration includes in its organization a container comparatively wide with regard to its length, but of relatively low height or depth. Oppositely-disposed, internal and external guides are formed with the open top of the container, the bottom whereof is raised or offset inwardly of the same. Over the open top is placed a cover divided in two substantially equal parts, one of which is affixed to the corresponding portion of the external guide, while the other can be swung up and down about a hinge that connects these parts together. The arrangement is such that the free portion of the cover may be moved at will either into closing position over the subjacent end of the container, or else folded back upon the fixed portion which permanently closes the container at the opposite end. Received between the internal guides beneath the hinged section of the cover, is a slidable closure member, slightly longer than the movable section, and serving in sublying registration therewith to prevent matter deposited in the container from reaching the cover thereabove. This member has one of its transverse ends in scraping contact with the fixed cover section, making a tight joint thereagainst, while the other end of the member provides a grip wherewith the same can be manipulated. The movable section of the cover carries, on the inside thereof, an element which can be forced into engagement with an abutment formed with the slidable closure member referred to, at such times as the movable cover section is brought down thereupon. The element named may be of a nature adapting it to hold an object placed thereon, particularly when the movable cover section is open or swung back upon the stationary section to which it is hinged. One side of a depression or pocket extending inwardly of the container, from the movable cover section thereof, conveniently constitute the abutment spoken of above. Within this pocket, which may be made fairly large, can be accommodated the element previously mentioned, the same affording a suitable means for interrelatively locking the outer movable cover section and the inner slidable closure member, one to the other.

The advantages of the invention as here outlined are best realized when all of its features and instrumentalities are combined in the one and same structure, but, useful devices may be produced embodying less than the whole.

It will be obvious to those skilled in the art to which the invention appertains, upon becoming conversant with the details thereof, that the same may be incorporated in several different constructions. The accom-

panying drawing, therefore, is submitted merely as showing the preferred exemplification of the invention.

Referring now to the aforesaid views, for a detailed description of the invention forming the subject-matter hereof, the numeral 11 denotes a receptacle primarily intended to receive what may be termed smokers' refuse, such as ashes from cigars or cigarettes, or extinguished butts thereof, or the consumed contents of a tobacco pipe, burnt matches, and waste matter of like nature. This receptacle is oblong in outline, although made comparatively broad with respect to its length, and of relatively, shallow proportion, as regards its depth or height, so as to afford an article that is convenient to carry in a person's pocket.

As shown, the receptacle 11 comprises longitudinal side walls 12, which are joined by rounded ends 13. Both the side and end walls are preferably made to bulge outwardly, as indicated at 14, 15, respectively, that is, they are given convex curvatures, for the purpose of enhancing their appearance, and moreover to increase the capacity of the receptacle, as well as to impart additional strength to it, particularly if fashioned from thin and light material, as at present contemplated. Access to the interior of the receptacle is had through its upper side, preferably.

Top and bottom portions 16 and 17, of the receptacle 11, are contracted relatively to its central part, as will be noticed upon reference to Figs. 2 and 3. The bottom portion 17 is somewhat smaller than the top portion 16, in the form of the invention illustrated. The upper edge of this top portion, which is slightly rolled over as shown, forms together with a fillet 18, joining it to the swelled-out central parts 14 and 15, a reversed curve 19. Thus, there is provided a convex retainer or guiding surface 20 exteriorly of the receptacle, and internally thereof another guide 21, concave and narrower, located substantially opposite the former.

From its base line 23, the underside of the said bottom portion 17 is raised, as at 24, inwardly of the receptacle. This prevents the contents of the latter, if hot, from transmitting excessive heat to a table or other primary support upon which the device may be temporarily rested, due to the fact that a layer of air is confined beneath the raised bottom 23, which thus provides a desirable insulation.

Overlying the open top side of the receptacle 11, is a sectional cover, composed by preference of two substantially equal parts, one of which 26 is provided on three sides thereof with an inwardly crimped rim 27, conforming in shape to the underlying portion of the guide 20 and adapted to em-

brace the same tightly, so that the said sectional part 26 of the cover is fixedly anchored in place thereon. Flexibly attached to the inner transverse edge of this fixed cover section 26, as by means of a hinge 29, is the other sectional part 30, which is movable and constitutes a lid for the open portion of the receptacle thereunder. The movable cover section 30 can either be laid down over the 10 said open portion, with its depending flanges 31 shielding the adjacent exposed portion of the guide 20 on the receptacle, or else it may be swung about the hinge 29, upwardly, and rearwardly as far back as 15 the top of the companion section 26, so as to lie upon it as represented in Figs. 2 and 5, in which inverted position the movable lid constitutes an upwardly facing open trough.

20 Slidably maintained within the internal guide 21, is a closure member 33, which, when moved to the extreme left end of the receptacle 11, as depicted in Fig. 3, serves to shut the open portion thereof 25 directly under the lid 30. The member 33 reaches approximately from the free or unincumbered end of the lid to a point a short distance beyond the inner transverse edge of the fixed cover section 26, that is, to 30 the right of the movable cover section 30, as shown in the figure last named.

The opposite cross-wise extending ends of the slidable closure member 33 are preferably turned upwardly, as Fig. 3 shows, the 35 one on the left, designated by the numeral 34, conforming to the inside contour of the before-mentioned top portion 16 of the receptacle, while that on the right, marked 35, constitutes a rearwardly projected lip 40 which stands in scraping relation to the underside of the anchored cover section 26. The up-turned parts 34 and 35, may both be considered, in fact, as upstanding lips, the purpose of which is to form seals 45 designed to check the escape of the contents of the receptacle. The outer lip 34, on the left-hand side, serves in addition as a grip or finger-hold wherewith the member 33 can be manipulated, to slide the same into or 50 out of either of its closed or open positions.

When the movable lid and the slidable member thereunder are in superimposed relation as illustrated by Fig. 3, it will be 55 readily seen that they form together a double closure, so constituted and arranged that no matter how the receptacle in its entirety is handled or thrown about, the refuse contained therein cannot reach the lid 30, by reason of the fact that the slide 33 keeps it off the same. Conversely, it is 60 obvious that nothing can touch the outer face of the slide from the exterior of the closed lid. From the foregoing it will be 65 understood that at such times as the latter

is swung open, the underside thereof is in clean condition, nothing having adhered to it that would cause unsightliness or soil the fingers of the person operating the device.

Notwithstanding that the slidable closure member 33 can be fitted reasonably tight within the guide 21, and the flanges 31 of the movable cover section 30 may be made to hug the guide 20 fairly close, that is, 70 sufficiently for either or both of the said parts 30 and 33 to be retained by frictional contact in their assigned positions, still it has been deemed advisable to furnish a special means for interrelatively locking 75 the same, i. e. one to the other. Such a means may conveniently consist of a retaining element, as 37, carried by one of the members of the said double closure, and co-operating with an abutment or engaging 80 part 38, provided on the other member thereof. A practical embodiment of the retainer 37 may be in the nature of a bifurcated semi-resilient tongue projecting at 85 substantially right angles from the inside 90 face of the movable cover section 30, and secured thereto, as by a rivet 39, passing through a flange 40, disposed in offset relation to the said tongue, which as illustrated 95 is located at a predetermined distance from the free extremity of the movable cover section. By preference, the abutment 38 is included with one of the 100 sides of a pocket or depression 42, which as shown may extend downwardly from the slidable closure member 33, interiorly of the receptacle 11. The coaction between the retaining element 37 and the engaging part 38 occurs at right angles to 105 the direction of movement of the slidable member 33, and approximately so to the movable lid 30, at the last part of its travel.

It will be readily perceived that, unless the retainer 37 and the abutment 38 are put or brought into alignment, the locking 110 action before spoken of cannot be effected. Precaution must be taken, therefore, to insure that the closure member 33 bears hard against the extreme left-hand side of the guide 21, in order to locate the engageable 115 edge of the pocket or depression 42 so that the tongue element will register therewith. If the member 33 is placed in the position just named, it will be plainly seen that egress from the receptacle 11 is completely 120 blocked.

Whenever it is desired to disengage the retaining element 37 from the contacting abutment 38, pertaining to the depression 42, 125 incidentally to swinging back the lid 30 into the position thereof depicted in Fig. 2, it is an easy matter to pry up the latter, by placing the nail of one finger under the free outermost, left-hand edge of its forward flange 31, and pushing or pulling thereon in 130

an upward direction. Then the element 37 will be drawn away from frictional or crowding contact with the adjacent side of the pocket or depression 42. It will be noticed that in the position last referred to, and as exemplified in Fig. 5, the bifurcated element 37 is substantially erect, and affords a rest or temporary support for one end of a cigar or cigarette laid thereon, normally the 10 lighted and ash-producing end. The ashes are readily caught by the similarly-arranged, bordering flanges 31 of the movable cover section or lid 30, that is, such ashes as may have fallen off the burning cigar or 15 cigarette, and which are easily chuted into the receptacle 11, provided of course the inner closure member 33 has been previously opened for the purpose. This is done by sliding back the member 33, to the right- 20 hand end of the receptacle, as indicated by dotted lines in Fig. 2, and then the collected ashes can be dumped into the forward end, on the left as shown, by simply tilting the lid about its hinge at the required inclina- 25 tion.

Although the herein disclosed arrangement of co-operating double closure members has been described herein with particular reference to a portable cinerary receptacle, fit to be carried in a smoker's pocket for use at various times and places, it stands to reason that the same can equally as well be applied to different species of containers or receivers for any other appropriate purpose.

While a certain preferred embodiment of this device has been shown and described, it will be understood that changes in the form, arrangements, proportions, sizes and details 40 thereof may be made, without departing from the scope of the invention as defined by the appended claims.

Having described my invention what I desire to secure by Letters Patent and 45 claim, is:—

1. A device of the character described including in combination, a receptacle adapted temporarily to store matter deposited therein, a sectional cover extending over the same, part of said cover being stationary and another part thereof movable, and a slide contained entirely within said receptacle, being coextensive with said movable part of the cover forming therewith a dual closure.

2. A device of the character described including in combination, a receptacle for the deposit of waste matter, a cover therefor composed of a fixed section and a movable section flexibly connected therewith, a slideable closure member normally carried in apposition to said movable cover section at the receiving end of the receptacle, being contained entirely within the latter, and means 60 serving ordinarily to maintain said member

in tightly closing position so that the matter thereunder may not come into contact with the overlying cover section.

3. A device of the character described including in combination, a container designed 70 for the reception of detrital matter, a sectional cover overlying the same, a movable lid constituting a part of said cover while the remaining portion thereof is fixedly anchored in position, a slideable closure member wholly encompassed by said container underlying said lid, and interengaging elements carried by said member and the lid operating to lock them together in such a way that the former may not be displaced 80 without first raising the latter.

4. A device of the character described including in combination, a container provided with an opening in the upper part thereof, and a dual closure for said opening, consisting of juxtaposed members respectively adapted, one to slide and the other to oscillate with relation to the container, both of said members remaining in either open or closed condition within the contour of the 90 latter.

5. A device of the character described including in combination, a container partly open at its upper side, a double closure for the opening therein composed of interrelatively movable members admitting normally to be held in juxtaposition, one of said members being oscillatable and the other slideable, both of said members remaining within the contour of said container whether open 100 or closed, and means capable of locking the members together so as to retain the same over said opening until a positive movement is effected to force them apart from each other.

6. A device of the character described including in combination, a receptacle provided with an opening at the top near one end, a lid for said opening arranged to swing to and from the same, a juxtaposed member commensurate with the opening slideable thereacross beneath said lid, being contained entirely within said receptacle, and means enabling said member to be retracted, subsequently to raising the lid, in order to 110 open the receptacle.

7. A device of the character described including in combination, a receptacle having an open upper side, a sectional cover fixedly retained over said open side at one end, a 120 movable lid forming a part of said cover at the other end of the receptacle, and a closure member slideable under both said lid and the fixed end section of the cover, alternately co-operating therewith, said closure member being contained entirely within the said receptacle in either open or closed condition.

8. A device of the character described including in combination, a receptacle initially open at the upper side thereof, a sectional 130

- cover laid upon said side, one section of said cover being rigidly held over part of the latter, another cover section constituting a movable lid for the remaining opening in 5 the receptacle, a closure member slideable under both of said sections, being constantly retained within said receptacle, and means operable to lock said lid and said member together at a point in the receptacle away 10 from the fixed part of the cover.
9. A device of the character described including in combination, a receptacle provided with an opening at the upper side near one end thereof, dual guiding means enclosing 15 said opening, a lid member engageable by one of said means, and a closure member in engagement with the other guiding means designed to act in conjunction with said lid, said closure being constantly 20 within the receptacle, said members being normally in co-operative juxtaposition at the open side of the receptacle.
10. A device of the character described including in combination a receptacle 25 formed with an open side, guides adjacent to said side respectively provided exteriorly and interiorly of the receptacle, a lid adapted to engage the external guide, and a closure member contained at all times entirely 30 within said receptacle engaging the internal guide subjacent to said lid, the latter and said member being interrelatively movable so as to bring them normally into juxtaposition.
11. A device of the character described including in combination, a receptacle provided with substantially oppositely disposed 35 guides, a cover section held partly in fixed position by one of said guides, a lid operatively connected to said section, and a closure member movable relatively to the other one of the guides in co-operative juxtaposition alternately to both the fixed cover section and the lid, said member being at all times entirely contained within said receptacle.
12. A device of the character described including in combination, a receptacle open at the upper side, a double closure therefor consisting of movable outer and inner members 45 adapted to be held in co-operative juxtaposition, the inner one of the members being constantly encompassed by the receptacle, and means also within said receptacle for interrelatively locking said members together.
13. A cinerary receptacle having a dual closure composed of coacting oscillatable and translatable outer and inner members, and co-operating engaging and engagement elements carried by said members respectively, the inner one of the members and one of the elements being at all times encompassed by said receptacle, said elements operating interrelatively to lock the latter in predetermined position within the receptacle.
14. A cinerary receptacle having a dual closure composed of coacting lid and slide members in juxtaposition at the open side thereof, an element projecting from one member of said closure, and a part included in the other member thereof arranged to receive said element so as to lock said members in closed position.
15. A cinerary receptacle having a dual closure composed of coacting juxtaposed oscillatable and reciprocable members, an element depending from the oscillatable member, and a pocket provided on the reciprocable member adapted to receive said element to lock said members in closed position one with the other.

ROBERT E. TORNBLOM.
